UNITED STATES PATENT OFFICE.

HARRY M. ST. JOHN, OF DETROIT, MICHIGAN.

DOOR CONSTRUCTION FOR REFRACTORY-FURNACE DRUMS.

Application filed October 10, 1922. Serial No. 593,645.

To all whom it may concern:

Be it known that I, HARRY M. ST. JOHN, a citizen of the United States, residing at Detroit, county of Wayne, State of Michigan, have invented a certain new and useful Improvement in Door Constructors for Refractory-Furnace Drums, and declare the following to be a full, clear, and exact description of the same, such as will enable others skilled in the art to which it pertains to make and use the same, reference being had to the accompanying drawings, which form a part of this specification.

This invention relates to a door construction for refractory furnace drums, and has for its object an improved organization of parts by means of which the charging door or aperture of the drum may be effectively closed while the metal-treating operation is in progress, and yet made available for easy opening and even removal when the recharging or cleaning of the interior of the drum becomes necessary.

In the drawings:

Figure 1 is a front elevation view of the door in closed position relatively to the surrounding furnace wall, which is indicated fragmentarily.

Figure 2 is a plan view from above, bringing out particularly the relative positioning of the hinges and of the door frame.

Figure 3 is a side sectional elevation, taken through the broken line 3—3 of Figure 1, showing the door in closed position in full lines and in open position in dotted lines.

The conditions of use of a refractory metal-treating furnace, particularly a rotatable or rockable one, involve as a prime necessity the firmness and tightness of closure of the door when the furnace is in use; at the same time the easy opening or removal of the door for charging or cleaning the furnace interior is equally important, and because of the intense heat developed within the furnace drum, it is similarly essential that the interior heat-facing portion of the door be formed of an appreciable thickness of refractory material, held in place however, by an exterior metal shell which easily lends itself to mechanical fastening and handling. Furthermore, the entire removal of the door under certain conditions renders highly desirable the use of an easily detachable hinge construction.

To this end I have devised the improved construction herein disclosed, consisting of

a refractory drum or wall A, having its edges about the charging aperture suitably armored, as by the frame B, to prevent abrasion and to support the necessary hinging and locking members. At the top of the door frame the metal is formed into two or more pairs of projecting knobs C, which support the horizontal pins or bars D, which are so positioned relatively to the extreme outer edge of the frame B, and to the complementarily shaped door shell E, that when the door is in the closed position shown in full lines in Figure 3, the nose G of the hinge hook F overengages each pin D to such an extent that the door cannot be removed by a straight horizontal move outwardly. In this position the shell E holds the refractory inner facing H of the door in such position that its upper and inner point J cooperates with the nose G in affording a mechanical locking against undesired dismounting of the hinges. When, however, the door is swung to the dotted line position shown in Figure 3, the point J of the refractory lining H is swung so far away from the adjacent overengaging edge of the furnace wall proper, that the door may now be lifted upwardly and outwardly sufficiently to terminate the holding engagement of the nose G over the pin D of each hinge. When the replacement of the door is desired, a reversal of this operation is necessary, that is, the door must be moved into position relatively to its hinges in the oblique manner indicated by the dotted lines in Figure 3, until the nose of each hook F engages over the pin D; the lower edge is then swung about each pin D as a rotative center until the door attains the closed, full-line position shown, when the upper edge J again functions cooperatively with the other parts described in preventing the dismounting of the door from its hinges.

As shown in Figure 1 particularly, the door may thereafter be locked against opening by inward swinging of the cam pieces K, which are located on each side of the frame B, preferably mounted upon suitable brackets L. The opening of the door, when a charge of metal is to be inserted, may be effected by inserting a hoisting chain or the hooked end of a draw bar in the loop M. In some positions of the door, particularly as it is about to be opened after the plastered-up edgings have been broken, it is advisable to start lifting it by inserting

draw bars in one or both of the obliquely positioned sockets R.

As brought out in Figures 1 and 3, the pouring spout Q projects from the furnace frame below the door aperture, being blocked up and sealed against egress of the molten metal until the mass is ready for the drum to be tilted for pouring. It will be noted, from an examination of Figure 1, that the metal shell E of the door is cut away immediately above the pouring spout as at T, exposing the refractory lining H accordingly. While not essential, I have found this to be frequently desirable to prevent injurious heating of the metal frame due to its proximity to the stream of molten metal when the spout is opened.

What I claim is:

1. In combination with an apertured refractory furnace wall and an encircling metallic frame therefor, a door comprising a metallic frame and an interiorly extending refractory lining, the upper edge of said door frame being formed into overengaging hook portions adapted to engage complementarily located supporting rods on said metallic frame, which, in cooperation with the close fit of the surrounding edges of the apertured furnace wall about the edges of the refractory lining of the door when in closed position, serve to prevent displacement of said hook portions from their supporting rods.

2. In combination with an apertured furnace wall and a metallic door frame located in bordering position thereabout, a plurality of horizontally positioned hinge stems on the upper edge of said door frame, a metallic door provided with an interiorly projecting refractory facing adapted to fit closely within said door frame and its surrounding refractory furnace wall, and hook

members located on the upper edge of said door in corresponding positions to the hinge stems on the door frame, adapted to interlock therewith against lifting removal of the door except when the latter is swung to open position.

3. The combination, with an apertured furnace wall, of a metallic bordering frame having its upper edge formed to support hinge bearings, a metallic door shell having on its upper edge bearing hooks complementarily positioned with respect to said hinge bearings which are capable of being made to engage and be disengaged from the same only when the door shell is in predetermined oblique position, and a refractory inner facing for said door, having its upper shoulder adapted to cooperate with the bordering frame in preventing the dismounting of the door when in substantially vertical position.

4. In combination with an armoring door frame, a metallic door provided with a refractory inner facing adapted to fit closely within said door frame, and separable hinge members whose parts are carried by said door frame and by said metallic door respectively, and with which said refractory inner facing is adapted to cooperate, by engagement against the surrounding edges of said door frame, in preventing the disassociation of said hinge members and the consequent dismounting of the door except when the door is raised to a predetermined oblique position.

In testimony whereof, I sign this specification in the presence of two witnesses.

HARRY M. ST. JOHN.
